[57] CLAIM

The ornamental design for a packaging container for computer product, as shown and described.

DESCRIPTION

FIG. 1 is a perspective view of a packaging container for a computer product showing our new design; FIG. 2 is a top perspective view thereof, with lids in closed position;

FIG. 3 is a bottom plan view of FIG. 2;

FIG. 4 is a top plan view of FIG. 2;

FIG. 5 is a right side elevation of FIG. 2;

FIG. 6 is a left side elevation of FIG. 2, and

FIG. 7 is a front elevation thereof, the rear side elevation is similar to the front elevation.

FIG. 1

FIG. 2

FIG. 3

FIG. 4

FIG. 5

FIG. 6

FIG. 7
